(57) **ABSTRACT**

A compound archery bow includes a bow handle having projection limbs, and first and second pulleys mounted on the limbs for rotation around on axles. A bow cable arrangement includes a bowstring cable extending from a bowstring anchor through a bowstring let-out groove at the first pulley and then toward the second pulley, a first cable extending from a first anchor through a portion of a groove on the first pulley and then toward the second pulley, and a second cable extending from a second anchor through a portion of a groove on the first pulley and then toward the second pulley. The first cable includes a yoke having a first end connected to the first anchor, a split second end connected to the first axle on opposite sides of the first pulley, and a third end extending toward the second pulley. The yoke preferably includes an idler pulley mounted on a bracket. The first cable preferably extends around the idle pulley between the first and second ends, and the third end extends from the bracket toward the second pulley. The second pulley and the bow cable arrangement at the second pulley, including the yoke, preferably are near mirror images of each other at the first and second pulleys.

COMPOUND ARCHERY BOW

The present disclosure relates to compound archery bows, including crossbows, having pulleys at the ends of the bow limbs to control the force/draw characteristics of the bow, and more particularly to an improvement in bows of this type to reduce the torque and friction applied to the pulley axles as the bow is drawn and released.

BACKGROUND AND SUMMARY OF THE DISCLOSURE

Single-cam and dual-cam compound archery bows have a power cam mounted on one or both ends of the bow limbs to control the draw force on the bowstring and bending of the limbs as the bowstring is drawn. A general object of the present disclosure is to provide a compound archery bow of the described type in which performance is improved by reducing friction and torque applied to the pulley(s).

The present disclosure embodies a number of aspects that can be implemented separately from or in combination with each other.

A compound archery bow, in accordance with one aspect of the present disclosure, includes a bow handle having projection limbs, and first and second pulleys mounted on the limbs for rotation on respective axles. A bow cable arrangement includes a bowstring cable extending from a bowstring anchor through a bowstring let-out groove at the first pulley and then toward the second pulley, a first cable extending from a first anchor through a portion of a groove on the first pulley and then toward the second pulley, and a second cable extending from a second anchor through a portion of a groove on the first pulley and then toward the second pulley. The first cable includes a yoke having a first end connected to the first anchor, a split second end connected to the first axle on opposite sides of the first pulley, and a third end extending toward the second pulley. The yoke preferably includes an idler pulley mounted on a bracket. The first cable preferably extends around the idle pulley between the first and second ends, and the third end extends from the bracket toward the second pulley. The first and second pulleys, and the bow cable arrangement at the pulleys, including the yokes, preferably are near mirror images of each other.

A compound archery bow, in accordance with another aspect of the present disclosure, includes a bow handle having projecting limbs, with at least a first of the limbs having a split end. First and second pulleys are mounted on the limbs for rotation on respective axles, with the first pulley being mounted on its associated axle within the split end of the first limb. A bow cable arrangement includes a bowstring cable extending from a bowstring anchor through a bowstring let-out groove at the pulley and then toward the second pulley. A first cable extending from a first anchor through a portion of a groove on the first pulley and then toward the second pulley, and a second cable extending from a second anchor through a portion of a groove on the first pulley and then toward the second pulley. The first cable includes a yoke having a first end connected to the first anchor, a second end anchored at the first axle within the split end of the first limb, and a third end extending toward the second pulley. The yoke preferably includes an idler pulley mounted on a bracket. The first cable preferably extends around the idler pulley between the first and second ends, and the third end extends from the bracket toward the second pulley. The first and second pulleys, and the bow cable arrangement at the pulleys, including the yokes, preferably are near mirror images of each other.

the bow cable arrangement at the pulleys, including the yokes, preferably are near mirror images of each other.

BRIEF DESCRIPTION OF THE DRAWINGS

- 5 The disclosure, together with additional objects, features, advantages and aspects thereof, will best be understood from the following description, the appended claims and the accompanying drawings, in which:
- 10 FIG. 1 is a side elevational view of a compound archery bow in accordance with a first exemplary embodiment of the present disclosure in its rest or undrawn condition;
- 15 FIGS. 1A and 1B together comprise end elevational views of the pulleys and bow cable arrangement in the bow in FIG. 1;
- 20 FIGS. 1C and 1D together comprise side elevational views of the pulley and bow cable system in FIG. 1 viewed from the side opposite FIG. 1;
- 25 FIG. 2 is a side elevational view of the bow in FIGS. 1-1D in the fully drawn condition;
- 30 FIGS. 2A and 2B together comprise a side elevational view of the pulleys and bow cable arrangement in the bow of FIG. 2;
- 35 FIG. 3 is a side elevational view of a compound archery bow in accordance with a second exemplary embodiment of the present disclosure in its rest or undrawn condition;
- 40 FIGS. 3A and 3B together comprise an end elevational view of the cam and cable system in the bow of FIG. 3;
- 45 FIGS. 3C and 3D together comprise a side elevational view of the pulley and cable system in the bow of FIG. 3 viewed from the opposite side as compared with FIG. 3;
- 50 FIG. 4 is a side elevational view of the bow in FIG. 3 in its fully drawn condition;
- 55 FIGS. 4A and 4B together comprise side elevational views of the pulley and cable system of the bow in FIG. 4;
- 60 FIG. 5 is a side elevation view of a compound archery bow in accordance with a third exemplary embodiment of the present disclosure;
- 65 FIGS. 5A and 5B together comprise a side elevational view of the pulleys and cable system in the bow of FIG. 5 at its rest or undrawn condition;
- 70 FIGS. 5C and 5D together comprise an end elevational view of the pulley and cable arrangement in the bow of FIG. 5;
- 75 FIG. 6 is a side elevational view of the bow in FIG. 5 in its fully drawn condition;
- 80 FIGS. 6A and 6B together comprise a side elevational view of the pulley and cable arrangement in FIG. 5 in the fully drawn condition of FIG. 6;
- 85 FIG. 7 is a side elevational view of a modification to the bow of FIG. 1;
- 90 FIGS. 7A-7B together comprise an end elevational view of the bow pulleys and cable arrangement in FIG. 7;
- 95 FIGS. 7C and 7D together comprise a side elevational view of the pulley and cable arrangement in the bow of FIG. 7 as viewed from the opposite side as compared with FIG. 7;
- 100 FIG. 8 is a side elevational view of a modification to the bow of FIG. 3;
- 105 FIGS. 8A and 8B together comprise an end elevational view of the bow pulley and cable arrangement in FIG. 8;
- 110 FIGS. 8C and 8D together comprise a side elevational view of the bow pulley and cable arrangement in the bow of FIG. 8 as viewed from the opposite side of FIG. 8;
- 115 FIGS. 9 and 10 are elevational views of crossbows in accordance with respective further exemplary embodiments of the disclosure;

FIG. 11 is a side elevational view of a compound archery bow in accordance with a further exemplary embodiment of the present disclosure;

FIGS. 11A and 11B together comprise an end elevational view of the bow pulley and cable arrangement in FIG. 11;

FIGS. 11C and 11D together comprise a side elevational view of the bow pulley and cable arrangement in the bow of FIG. 11 as viewed from the opposite side of FIG. 11;

FIG. 12 is a side elevational view of a compound archery bow in accordance with yet another exemplary embodiment of the present disclosure;

FIGS. 12A and 12B together comprise an end elevational view of the bow pulley and cable arrangement in FIG. 12;

FIGS. 12C and 12D together comprise a side elevational view of the bow pulley and cable arrangement in the bow of FIG. 12 as viewed from the opposite side;

FIG. 13 is a side elevational view of a compound archery bow in accordance with yet another exemplary embodiment of the present disclosure;

FIGS. 13A and 13B together comprise an end elevational view of the bow pulley and cable arrangement in FIG. 12;

FIGS. 13C and 13D together comprise a side elevational view of the bow pulley and cable arrangement in the bow of FIG. 12 as viewed from the opposite side; and

FIG. 13E is an exploded perspective view of the upper pulley in the embodiment of FIGS. 13A to 13D.

DETAILED DESCRIPTION OF PREFERRED EMBODIMENTS

FIGS. 1-1D illustrate a compound archery bow 100 in accordance with a first exemplary embodiment of the present disclosure in its rest or undrawn position, while FIGS. 2-2B illustrate the same bow 100 in its fully drawn condition. Bow 100 includes a handle 19 of aluminum or other relatively rigid construction having spaced risers with limb-mounting surfaces at each end. A pair of flexible resilient limbs 20 of fiber-reinforced or other suitable resilient construction are mounted on their respective handle risers and project away from handle 19. An upper pulley 21 is mounted on upper limb 20 for rotation on an axle 4, and a lower pulley 22 is mounted on an end of lower limb 20 for rotation on an axle 4. The axles can be integral with the pulleys and rotatable in bearings on the limbs, or can be separate from the pulleys and the pulleys rotatable on the axles. Bow 100 is a dual-cam bow in which pulleys 21, 22 are similar in function and preferably near mirror images of each other. (Upper pulley 21 can be slightly larger than lower pulley 22 to compensate for the arrow rest not being at the true center of the bow. The pulleys also can be made non-identical in areas that are non-functional to create a difference in appearance.)

Bow 100 has a bow cable system or arrangement that includes a bowstring cable 11 extending from an anchor 5 at pulley 21 around a peripheral let-out groove 15 (FIG. 1A) across handle 19, around a peripheral let-out groove 15 at pulley 22 and then to an anchor 5 at pulley 22. (The terms "let-out" and "take-up" are used in their conventional senses to refer to grooves that "let-out" cable or "take-up" cable as the bowstring is drawn away from the bow handle.) A pair of cables 9, 10 extend between pulleys 21, 22 to control rotation at their respective pulleys as bowstring 11 is drawn. In the exemplary embodiment of FIGS. 1-2B, cable 9 extends from an anchor 13 through a portion of a groove 16 and then toward pulley 22. Approaching pulley 22, cable 9 attaches to a yoke pulley assembly 17, of which one end 9a extends through a portion of a groove 16 at pulley 22 and then to an anchor 14. The other end 9b is coupled to axle 4, preferably split on

opposing sides of axle 4 as best seen in FIG. 1B. The cable connection at yoke pulley assembly 17 preferably includes an idler pulley 6 rotatably mounted on a bracket 8. Cable 9a is trained around pulley 6 before being split at ends 9b. Cable 9 is anchored to bracket 8.

Cable 10 likewise extends from an anchor 13 at pulley 22 through a portion of groove 16 at pulley 22 and then attaches to yoke pulley assembly 17 with a cable end 10a extending through a groove portion 16 to an anchor 14. The other end 10b of the yoke at cable 10 is split and coupled to axle 4 on opposite sides of pulley 21 as best seen in FIG. 1B. Yoke pulley assemblies 17 preferably are identical, each comprising an idler pulley 6 rotatably mounted on a bracket 8. Again, cable portion 10a and split portions 10b are trained around pulley 6 while cable 10 extends from bracket 8 to anchor 13 at pulley 22. Pulleys 21, 22 and cables 9, 10, including yoke pulley assemblies 17 and split ends 9a, 9b and 10a, 10b, preferably are near mirror images of each other.

As bowstring 11 is drawn away from handle 19 in the embodiment of FIGS. 1-2B, bowstring 11 is let out from bowstring let-out grooves 15 at their respective pulleys. This causes rotation of the respective pulleys on their axles. Cable end 10a is let out from groove 16 at pulley 21 while cable end 9a is let out from groove 16 at pulley 22. Cable 9 is taken up into groove 16 at pulley 21 and cable 10 is taken up into groove 16 at pulley 22. Thus, in this embodiment, cable is simultaneously let out from and taken up into different portions of groove 16 at the respective pulleys. In the meantime, yoke pulley assembly 17 on cables 9, 10 apply a reduced load 20 to the pulley bearings by anchoring the split yoke cable directly to the axle on opposite sides of the pulley, reducing friction and torque at the bearing systems and improving performance. The limbs are more stable and resistant to torque because some of the cable load is distributed to the 25 axles outboard of the pulleys. By placing the yoke cable anchors outboard of the limbs, the slots at the ends of the limbs to accommodate the pulleys can be reduced in size. When using two individual limb sections (as distinguished from a single split limb) at each end of the bow, the limb 30 sections can be placed closer together.

FIGS. 1-2B illustrate an exemplary embodiment of the present disclosure having two grooves at each pulley as disclosed in US 2010/0051005 (the disclosure of which is incorporated herein by reference) and with the yoke pulley assemblies 17 in the cable let-out system of the pulleys. FIGS. 3-4B illustrate a second exemplary dual-cam bow 200, this time with three grooves at each pulley as generally disclosed in U.S. Pat. No. 6,990,970B1 (the disclosure of which is incorporated herein by reference), and with the yokes again in the cable let-out portions of the cable system. Reference numerals in FIGS. 3-4B (and in FIGS. 5-13E) that are identical to reference numerals employed in FIGS. 1-2B indicate correspondingly identical or related components. In bow 200 of FIGS. 3-4B, the let-out grooves 28 for cable portions 9a, 10a 45 are separate from the take-up grooves 29 for cable portions 9, 10. Bowstring cable 11 in FIGS. 5-6B again extends from an anchor 12 at upper pulley 32 around a peripheral bowstring let-out groove 27, then across the bow handle to the bowstring let-out groove 27 on pulley 33 and then to an anchor 12 at 50 pulley 33. Cable 9 extends from an anchor 30 (FIG. 6A) through a portion of take-up groove 29 to yoke pulley assembly 17, and then at 9b to the opposite ends of axle 4 and at 9a to let-out groove 28 at pulley 33. Likewise, cable 10 extends from a take-up groove 29 on pulley 33 to yoke pulley assembly 17, and then at end 10a to let-out groove 28 and split ends 55 10b to the opposite ends of axle 4 at pulley 32. As bowstring cable 11 is drawn away from handle 19 in the embodiment of

FIGS. 3-4B, cables 9, 10 are taken up into grooves 29 and cable ends 9a, 10a are let out from grooves 28. Again, split cable sections 9b, 10b help balance the forces applied to the respective axles 4 and the forces applied to the bow limbs.

FIGS. 5-6B illustrate a bow 300 that is similar in many respects to bow 200 of FIGS. 3-4B. The primary differences between bow 200 and bow 300 are that the take-up grooves 29 and the let-out grooves 28 are on opposite sides of the bow-string let-out groove 27 on pulleys 32 and 33.

FIGS. 7-7D illustrate a bow 400 that is similar in many respects to bow 100 of FIGS. 1-2B. The primary difference between bow 400 and bow 100 is that the yoke pulley assemblies 17 in bow 400 are in the take-up paths of cables 36, 37 at pulleys 34, 35 rather than in the let-out paths of the respective cables 8, 9 in bow 100. Likewise, FIGS. 8-8D illustrate a bow 500 that is similar in many respects to bow 200 in FIGS. 3-4B except that yoke pulley assemblies 17 are in the take-up portions of cables 36, 37 at pulleys 38, 39 of bow 500 rather than in the let-out portions of cables 9, in bow 200.

FIGS. 9 and 10 illustrate respective crossbows 600 and 700 in accordance with additional exemplary embodiments of the disclosure. In each crossbow, flexible resilient limbs 44 are mounted on opposed ends of a handle riser 45. Pulleys are rotatably mounted on the ends of the limbs, pulleys 40, 41 in FIG. 9 and pulleys 42, 43 in FIG. 10. The bow cable arrangement in FIG. 9, including the yokes, is generally similar to that described in detail above in connection with FIGS. 1-2B, and the bow cable arrangement in FIG. 10 is generally similar to that described in detail above in connection with FIGS. 5-6B.

In the bow 800 of FIGS. 11-11D, the bow limbs 20 are split, and the pulleys 49, 50, including the cable anchors at axles 4, are disposed between the split sections of the limbs 20 at the ends of the limbs. At upper pulley 49, cable 10 is split at yoke pulley assembly 17, with a first portion 47 extending through a portion of groove 16 to anchor 14 and a second portion extending from yoke pulley assembly 17 to a cable spreader 46. End cable portions 48 extend from spreader 46 to anchor at axle 4 on opposite sides of pulley 49. The cable arrangement at lower pulley 50 is the mirror image of the system at upper pulley 49, with cable section 47 extending through a portion of groove 16 to anchor 14, and the opposite ends 48 extending from spreader 46 to anchor at axle 4 on opposite sides of pulley 50. The cable spreaders 46 allow the cables to clear the respective pulleys when anchored between the pulleys and portions of the limbs 20 lying outboard of the pulleys as shown in FIG. 11A (as distinguished from being outboard of the limbs as illustrated at 20 in FIG. 1A) and simplifies construction of the yoke cables. The cable spreader arrangement of FIGS. 11-11D could be employed in any of the embodiments of FIGS. 1-10.

In the bow 900 of FIGS. 12-12D, the bow limbs 20 again are split, and the pulleys 51, 52, including the cable anchors at axles 4, are disposed between the split sections of the limbs 20 at the ends of the limbs. (Reference to "split" limbs includes both solid limbs having a notch at the ends in which the pulleys and axles are disposed, and limbs that are divided from handle 19 outward with the limbs and anchors being disposed between the divided sections of the limbs adjacent to the outer ends of the limbs.) Cable end 53a extends through a portion of groove 16 to anchor 14 on pulley 51, and end 53b extends to and is anchored at axle 4. The cable connections at the other end of the bow are a mirror image of the cable connections at the upper end of the bow. Thus, the primary differences between the bow 900 in FIGS. 12-12D and the bow 100 of FIGS. 1-1D are that cable ends 53a in FIGS. 12-12D are not split as are cable ends 10b in FIGS. 1-1D, and

that cable ends 53 in FIGS. 12-12D are anchored to axles 4 within the bow limb split ends 20 rather than outboard of the bow limb split ends 20 as in FIGS. 1-1D. This feature is particularly useful in crossbow applications.

5 In the bow 950 of FIGS. 13-13E, The cable ends 58b, 59b are split and anchored at axe's 4 as in several previous embodiments, while the cable ends 58a, 59a encircle annular idlers 57 at each pulley. Each idler 57 is mounted on an associated boss 60, which is mounted on the associated pulley surrounding and eccentric to the axis the associated axle 4. This arrangement effectively moves the centers of the concentric idlers 57 to feed-out and take-up cables 58, 59 as the bow is drawn.

10 There thus has been disclosed a compound archery bow that fully satisfies all of the objects and aims previously set forth. The bow has been disclosed in conjunction with several exemplary embodiments, and modifications and variations have been discussed. Other modifications and variations 15 readily will suggest themselves to persons of ordinary skill in the art in view of the foregoing description. The disclosure is intended to embrace these and all other modifications are variations as fall within the spirit and broad scope of the 20 appended claims.

25 The invention claimed is:

1. A compound archery bow that includes:
projecting limbs,
a first pulley mounted on a first of said limbs for rotation on a first axle,
a second pulley mounted on a second of said limbs for rotation on a second axle, and
a bow cable arrangement including a bowstring cable extending from a bowstring anchor through a bowstring let-out groove at said first pulley and then toward said second pulley, a first cable extending from a first anchor through a portion of a groove on said first pulley and then toward said second pulley, and a second cable extending from a second anchor through a portion of a groove on said first pulley and then toward said second pulley,
characterized in that
said first cable includes a yoke having a first end connected to said first anchor, a split second end anchored at said first axle on opposite sides of said first pulley, and a third end extending toward said second pulley, and
said second pulley and said bow cable arrangement at said second pulley, including said yoke, are near mirror images of each other,
wherein said first cable extends from a let-out groove in said first pulley and said second cable extends from a take-up groove on said first pulley and said first cable and said second cable are simultaneously let out from and taken up into the same groove of said first pulley.
2. The bow set forth in claim 1 wherein said yoke includes a bracket and an idler pulley on said bracket,
said first cable extending around said idler pulley between said first and second ends,
said third end of said first cable extending from said bracket toward said second pulley.
3. The bow set forth in claim 1 wherein said bow is a crossbow.
4. The bow set forth in claim 1, wherein said first anchor includes an annular idler on a boss eccentric to an axis of the first axle, and said first end of said first cable is connected to said annular idler.

5. A compound archery bow that includes:
 projecting first and second limbs,
 a first pulley mounted on a first of said limbs for rotation on
 a first axle and a second pulley mounted on a second of
 said limbs for rotation on a second axle, and
 a bow cable arrangement including a bowstring cable
 extending from a bowstring anchor at said first pulley
 through a bowstring let-out groove at said first pulley
 across said handle and then through a bowstring let-out
 groove at said second pulley to a bowstring anchor at 10
 said second pulley,
 a first cable extending from a first anchor at said first pulley
 through a portion of a groove on said first pulley and then
 across said handle to a first yoke, said first cable having
 a first portion extending from said yoke through a portion
 of a groove on said second pulley and to an anchor at
 said second pulley, and a split second portion extending
 from said first yoke to anchor at said second axle on
 opposite sides of said second pulley, and
 a second cable extending from a second anchor on said
 second pulley through a portion of a groove on said
 second pulley and then toward said first pulley across
 said handle, said second cable including a second yoke
 from which a first end extends through a portion of a
 groove on said first pulley to a second anchor at said first
 pulley and a split second portion extending from said
 second yoke to anchor at said first axle on opposite sides
 of said first pulley,
 wherein said first cable extends from a take-up groove on
 said first pulley and a let-out groove on said second
 pulley, said second cable extends from a let-out groove
 on said first pulley and a take-up groove on said second
 pulley and said split second portion of said first cable is
 anchored within end portions of said first limb and said
 split second portion of said second cable is anchored
 within end portions of said second limb. 35

6. The bow set forth in claim 5 wherein said first and second
 pulleys and said bow cable arrangement at said first and
 second pulleys, including said yokes, are near mirror images
 of each other. 40

7. The bow set forth in claim 6 wherein each of said yokes
 includes a bracket and an idler pulley on said bracket. 45

8. The bow set forth in claim 7 wherein said second portions
 of said first and second cables include respective cable
 spreaders, and wherein said split portions of said first and
 second cables anchor to said axles on opposite sides of said
 pulleys between said pulleys and portions of said limbs lying
 outboard of said pulleys. 50

9. A compound archery bow that includes:
 projecting limbs,
 at least a first of said limbs having a split end,
 a first pulley mounted on said first of said limbs for rotation
 on a first axle within said split end,
 a second pulley mounted on a second of said limbs for
 rotation on a second axle, and
 a bow cable arrangement including a bowstring cable
 extending from a bowstring anchor through a bowstring
 let-out groove at said first pulley and then toward said
 second pulley, a first cable extending from a first anchor
 through a portion of a groove on said first pulley and then
 toward said second pulley, and a second cable extending 55
 60

from a second anchor through a portion of a groove on
 said first pulley and then toward said second pulley,
 characterized in that

5 said first cable includes a yoke having a first end connected
 to said first anchor, a second end anchored at said first
 axle within said split end of said first limb, and a third
 end extending toward said second pulley,
 wherein said first cable extends from a let-out groove in
 said first pulley and said second cable extends from a
 take-up groove on said first pulley and said split second
 end of said first cable is anchored at said first axle on
 opposite sides of said first pulley within said split end of
 said first limb.

10. The bow set forth in claim 9 wherein said yoke includes
 a bracket and an idler pulley on said bracket,
 said first cable extending around said idler pulley between
 said first and second ends,
 said third end of said first cable extending from said bracket
 toward said second pulley. 20

11. The bow set forth in claim 10 wherein said second
 pulley and said bow cable arrangement at said second pulley,
 including said yoke, are near mirror images of each other. 25

12. The bow set forth in claim 10 wherein said bow is a
 crossbow.

13. A compound archery bow that includes:
 first and second limbs;
 a first pulley mounted on a first of said limbs for rotation
 around a first axis;
 a second pulley mounted on a second of said limbs for
 rotation around a second axis;
 a first cable extending from bowstring let-out means on
 said first and second pulleys;
 a second cable extending from a take-up means on said first
 pulley and toward said second pulley, and connecting to
 a first idler pulley mounting bracket having a third axis;
 a third cable anchoring at one end to said second pulley,
 extending through a let-out means of said second pulley,
 extending around a first idler pulley, and splitting into
 split portions connecting to opposite sides of said second
 pulley;

a fourth cable extending from a take-up means on said
 second pulley and toward said first pulley, and connect-
 ing to a second idler pulley mounting bracket having a
 fourth axis; and

a fifth cable anchoring at one end to said first pulley and
 through a let-out means, extending around a second idler
 pulley, and splitting into split portions connecting to
 opposite sides of said first pulley.

14. The bow set forth in claim 13 wherein said split por-
 tions of said third and fifth cables are anchored, respectively,
 on opposite sides of the first and second pulleys within end
 portions of said limbs. 50

15. The bow set forth in claim 13 wherein said first cable
 and said second cable are simultaneously let out from and
 taken up into the same means of said first pulley, and said
 fourth cable and said fifth cable are simultaneously let out
 from and taken up into the same means of said second pulley. 55

16. The bow set forth in claim 13 wherein said bow is a
 crossbow. 60
